UNITED STATES PATENT OFFICE.

VÁCLAV KLÁN AND RUDOLF SEITZ, OF PRAGUE, BOHEMIA, AUSTRIA-HUNGARY.

CONSTRUCTION OF SASH-WINDOWS.

SPECIFICATION forming part of Letters Patent No. 355,091, dated December 28, 1886.

Application filed July 3, 1885. Serial No. 170,638. (No model.)

To all whom it may concern:

Be it known that we, VÁCLAV KLÁN and RUDOLF SEITZ, both of Prague, Bohemia, Austria-Hungary, have invented a new and useful construction of Improved Sash-Window with Outside Roll-Shutters, of which the following is a full, clear, and exact description.

The object of our invention is to provide a new and improved window provided with sliding sashes counterbalanced by weights, which are mounted in such a manner that they can be swung inward on hinges, for the purpose of facilitating the cleaning of the sashes or the repairing of the same.

15 This invention consists in a window having four sashes—an upper and a lower outer sash and an upper and lower inner sash—all the sashes being mounted to slide and to swing on pivots, all as will be fully described and 20 set forth hereinafter, and then pointed out in the claims.

Reference is to be had to the accompanying drawings, forming a part of this specification, in which similar letters of reference indicate 25 corresponding parts in all the figures.

Figure 1 is a face view of my improved window. Fig. 2 is a central vertical cross-sectional view of the same; the window being closed, on the line $x-x$, Fig. 1, looking in the 30 direction of the arrow x' . Fig. 3 is a like view looking in the direction of the arrow v' . Fig. 4 is a sectional plan view of a window on the line $v-v$, Fig. 1, the sashes being closed. Fig. 5 is a sectional view in the same plane, all the 35 sashes being lowered and swung in the direction toward the interior of the room on their pivots. Fig. 6 is a vertical sectional view in the plane of the window on the line $w-w$, Fig. 2. Fig. 7 is a detail side view of the device 40 for holding the weight-cords of the outer lower sash, parts being broken out and others in section. Fig. 8 is an enlarged sectional plan view of the sliding hinge for the outer upper sash. Fig. 9 is a sectional view on the line $v-v$, Fig. 45 3, parts being broken out, and others being in section. Fig. 10 is an enlarged detail sectional plan view of the weight and its clamping device. Fig. 11 is a detail view of the rod and mechanism for operating the latches. Fig. 50 12 is a partial face and a partial sectional view

of the inner lower sash. Fig. 13 is an edge view of the sash. Fig. 14 is a detail view of the block in which the sash chains or cords for the inner lower sash are secured. Fig. 15 is an enlarged detail sectional plan view of the lower hinge of the inner lower sash. Fig. 16 is an enlarged detail sectional plan view of the devices for locking the block on which the sash cord or chain of the lower inner sash is secured in place. Fig. 17 is a detail side view 60 of the hinge-socket piece of the lower hinge of the inner lower sash. Fig. 18 is a side view of the lower portion of one of the weights carrying the locking device.

A represents the inner upper sash, B the inner lower sash, C the upper outer sash, and D the lower outer sash. The window-frame E is provided in its sides with the vertical tongues A' B' D' and with the pulley-stile C', for guiding the sashes A, B, D, and C, which 70 slide vertically in the frame E. The sashes A, B, and D are provided in their side edges with vertical grooves for receiving said guide-tongues A' B' D', and through the said grooves the cords by which the sashes are suspended 75 can also be passed.

The sash cord, chain, and cable F is secured at one end to a hook, F, secured in the groove A' in the sash A, in that side edge at which the window is to be pivoted to swing—in this 80 case the left-hand side edge. The said rope or chain F is then passed over a pulley, F', at one of the upper corners of the frame—that is, the upper corner on that side of the frame corresponding to the side edge of the sash on 85 which the same is to be pivoted. It is then passed over the upper part of the face of the frame to and over the pulley F', at that corner of the frame opposite the one at which the pulley F' is located, from which it is passed 90 down within the casing and secured at its lower end to a weight, F", which is guided in a vertical groove, F⁵, in one of the side boxes of the frame—in this case the right-hand side. In a recessed portion of the said weight F" two 95 crossed levers, F⁶, are pivoted, the lower ends of which can be passed into notches F' and F⁸ in the sides of the groove F⁵, at the bottom of said groove and at about half the height of the same. The lower ends of said prongs or lock- 100

ing-levers F^6 are pressed outward—that is, from each other—by the springs F^9 , secured to the weight F^4 . Between the upper ends of said locking-levers F^6 a cam-piece, G^4 , is mounted on a shaft G , which is pivoted in the weight F^4 and passes through a vertical slot, G^2 , Figs. 4 and 5, in the piece covering the front of the groove F^5 , said shaft being provided at its outer end with a cross-piece or handle, G^3 , which may be ornamented, more or less.

In the piece G^4 , covering the front of the groove F^5 , a dovetailed sliding piece, G^5 , is provided to slide up and down, and said piece is provided in its lower part with a longitudinal groove, G^6 , through which the shaft G is passed. The said sliding strip G^5 is provided to cover the slot G^2 when the weight F^4 is lowered.

By turning the handle G^3 the cam-piece G^4 is turned and presses the upper ends of the locking-levers F^6 from each other, thereby withdrawing the lower ends of the said locking-levers from the notches F^7 or F^8 and thereby permitting of moving the weight F^4 up or down through the handle G^3 , whereby the sash A will be raised or lowered. The lower part of the guide-tongue A' , for guiding the swinging edge of the sash A when the said sash slides, is cut out, as shown at G^8 , Fig. 1, so as to permit of swinging the free edge—that is, the right-hand edge in this case—of the sash from the frame.

The sash A will be locked in place when raised, and this is accomplished by the bolt H , mounted to slide in that side of the frame in which the swinging edge of the sash slides in such a position that it can pass into a notch, H' , in the lower part of the side edge of the sash A when the said sash is raised. A spring, H^2 , presses the bolt H toward the swinging edge of the sash. Said bolt is provided with a longitudinal slot, H^3 , into which a guide-pin, H^4 , passes.

An angle-lever, H^5 , is pivoted in the frame of the window, one shank resting against an end lug of the bolt H and the other end resting on the upper end of a rod, H^6 , which extends down through the groove F^5 behind the weight F^4 , and is provided near its lower end with a lug, H^7 , resting on a cam, H^8 , mounted on the inner end of the shaft G , behind the weight, as shown in detail in Figs. 10 and 18. If desired, the angle-lever H^5 may be provided in that shank resting against the sliding bolt H with a longitudinal slot, through which a pin passes into the bolt. As the end of the bolt H is pressed against that part of the edge of the sash A above the notch H' , said edge is to be protected by means of a metal strip.

When the sash A is raised, it is locked in place automatically by the bolt H , and the same movement which unlocks the weight F^4 withdraws the bolt H , to release the said upper sash.

On the left-hand or pivoted edge of the upper sash, A , two hinged plates, I and J , are secured, which are provided with the down-

wardly-projecting hinge-pins I' and J' , of which the pin J' can be passed into the socket J^2 , fixed on the frame, and the pin I' can be passed into the hinge-socket I^2 , resting on the top of the hinge-plate J , and mounted to slide vertically on a rod, I^3 , (shown in Fig. 3,) and secured in the window-frame at that side of the same at which the pivoted edge of the upper sash is located, so that when said sash A is lowered the lower pin, J' , passes into the fixed socket J^2 , and the upper pin, I' , passes into the sliding socket I^2 , which slides down with the plate J until it arrives at the lower end of the rod I^3 , where it is held and prevented from descending any farther. When the said sliding socket I^2 is lowered as far as possible—that is, rests on the lower bent end of the rod I^3 , fastened to the frame—the distance between the fixed socket J^2 and the said socket I^2 will be equal to the distance between the hinge-pins I' and J' on the said upper sash.

When the hinge-pins on the upper sash have been lowered into their sockets, by lowering the sash, the sash can be swung toward the interior of the room, as shown in Fig. 5. When the said sash A is lowered, so that it can be swung out, as stated, the weight F^4 is raised and is held in the raised position by the locking prongs F^6 , which are passed into the upper notches, F^8 , in the sides of the grooves F^5 .

The lower inner sash, B , Fig. 12, is balanced by means of the weights K , secured to cords K' , passed over pulleys K^2 , Fig. 3, in the sides of the frame, the weights K working up and down in the boxes, each of which cords K' has its other end secured to a plate, K^3 , provided with a longitudinal slot, K^4 , and with a longitudinal half-bead, K^5 , adjacent to and parallel with the slot, which half-bead K^5 is mounted to slide in a groove, K^6 , in the corresponding pulley-stile K^7 of the frame, said plates K^3 being mounted between the backs of the pulley-stiles K^7 and the side edges of the said sash B .

In a recess, L , in the lower part of the pulley-stile a curved lever, L' , is pivoted and is provided at its upper end with a hook, L^2 , which can be passed through the top opening, L^3 , of the plate L^4 , which plate closes the recess or cavity L . The said plate L^4 is also provided with a bottom opening, L^5 .

The sash is provided with a groove, B^2 , for receiving the guide-bead B' , and near its lower end with a notch, B^3 , for receiving part of the plate K^3 .

In the bottom rail of the sash a longitudinal aperture, M , is formed, in which the two sliding bolts M' are mounted, which are connected by the links M^2 with the cross-piece M^3 on the inner end of the shaft M^4 , mounted to turn in the bottom rail of said sash, and provided on its outer end with a cross-piece or handle, M^5 , for turning it. A spring, M^6 , acts on one of the sliding bolts, and thus keeps the ends of both projected from the side edges of the sash, suitable apertured plates, M^7 , being provided, as shown in Fig. 13, through which the ends of the said bolts are guided. In that

end of the aperture or bore M nearest the hinged edge of the sash the link N is pivoted, which has one end connected with the sliding bolt M' and the other end connected with the bolt N', the outer end of which can also be projected from the side edge of the sash.

On the pivoted edge of the sash the hinged plates O and P are secured, from which the pins O' and P' project downward, which pins can be passed into the sockets O² and P², secured on the window-frame. Above the lower hinge-socket, P², the piece or half-socket P³ is passed through a slot in the plate P⁴ in such a manner that the said half-socket P³ can pass into and rest on the socket P², or can be pressed back within the recess behind the said plate P⁴. Said half-socket P³ is connected with a cam-piece, P⁵, also mounted in a slot in the plate P⁴, to slide through said slot, said cam having its upper end beveled.

As shown in Fig. 17, the cam P⁵ and the half-socket P³ are on opposite sides of the partition P⁶, secured on the back of the plate P⁴, said partition P⁶ being provided with the slot P⁷, through which the connecting-piece of the socket and cam passes. The spring P⁸, secured on the partition P⁶, acts on the inner part of the half-socket P³ and presses the same outward. The sliding bolt N' must be slightly in front of the sliding bolt M', with which it is connected, so that when the ends of the sliding bolts pass through the apertures in the plates M' the end of the sliding bolt N' can act on the outer end of the cam-piece P⁵, for the purpose of pressing the cam-piece through the slot in the plate P⁴ into the cavity behind the plate, and thereby also pressing the half-socket P³ through said plate. In Figs. 15 and 16 the details of the hinges and of the plates or blocks K³ are shown.

The lower outer sash is mounted in the same manner as the lower inner sash, and its weights Q are secured to cords, ropes, or chains Q', passed over pulleys Q² in the pulley-stiles, and having their other ends secured to blocks Q³, each block being provided with a half-bead, Q⁴, and with a downwardly-projecting arm, Q⁵, below the half-bead, which arm is provided with a longitudinal slot, Q⁶.

In the sill-piece R, Fig. 7, of the frame, a recess or slot, R', is formed for receiving the extension Q⁵ of each block Q³, one of the said slots or recesses being formed at each side of the window-frame. On the bottom cross-piece, R², against which the bottom edge of the outer lower sash can rest, sliding bolts R³ are provided, one at each side, which can be passed through the slots Q⁶ of the extensions Q⁵ of the blocks Q³, as shown in Fig. 7, for the purpose of locking the said blocks in place when the window is to swing. The lower outer sash, D, is also provided with the sliding bolts M', the shaft M⁴, having a handle, the cross-piece M³, and the links M², connecting the cross-piece with the bolts. The outer ends of said bolts can pass into notches Q⁸ in the blocks Q³, thus holding the blocks in place on the sides

of the said lower sash, which sash is provided with suitable recesses in the side edges for receiving said blocks.

The upper outer sash, C, is connected with a rope or cord, S, which is passed over a pulley, S', at the upper left-hand corner of the frame—that is, at that corner of the frame above the pivoted edge of said sash. Then the said cord or chain S is passed over suitable pulleys in the direction at right angles to the plane of the window to the pulleys S² at the inner side of the window-frame, Fig. 9, and is connected to a weight, S⁴, sliding in a groove, S⁵, constructed the same as the groove F⁵ in the window-frame, but being on the opposite side. The locking device and all other parts on the weight S⁴ are the same as those shown and described for the weight F⁴, and consequently there is no necessity of describing all these parts again. The covering-piece for the groove S⁴ is also provided with a slot and with a sliding piece, G³, all as stated. In the swinging edge of the said upper sash a notch, T, is provided for receiving the end of the sliding bolt T' in the side of the frame, which bolt is pressed into the notch by a spring, T². The inner end of the sliding bolt is connected with an angle-lever, T³, on which the inner end of the lever T⁴ acts, which is pivoted in the side of the casing at right angles to the plane of the window, and with the inner end of this lever the upper end of a rod, T⁵, is connected, which is located in the groove S⁵ in the same manner as the rod F⁶ is located in the groove F⁵, and said rod T⁵ is operated in the same manner from the cam-piece on the shaft in the weight S⁴ as the rod F⁶ is operated by a cam-piece on the shaft in the weight F⁴, which construction was fully described hereinbefore. Said upper outer sash, C, is provided with the two hinge-plates U and V, from which the hinge-pins U' and V' project downward. At the side of the lower pin, V', a cam-piece, W, is held, which projects above and below the hinge plate, and has its ends rounded. The lower hinge-pin, V', can be passed into a hinge-socket, V², fixed in the casing, and the upper hinge-pin, U', can be passed into the socket U², which is held on the plate U³ in the side of the casing in such a manner that it can pass in and out. At the side of said socket U² the cam-plate U⁴ is provided, which has its edge rounded, and on its edges the ends and edges of the cam-piece W and the lower hinge plate, V, can act. The said hinge-socket U² is provided in its inner part with a slot, U⁵, through which a guide-pin, U⁶, passes into the plate U⁷, connected with the plate U³. The spring U⁸ presses the said hinge-socket outward, the pin U⁶ in the slot U⁵ preventing the spring from pressing the socket outward too far.

If desired, all the sashes may be provided in their swinging or in both edges with rollers, which will cause them to slide more readily.

The bottom rail of the bottom inner sash is provided with a groove for receiving a tongue

on the cross-piece *a* on the sill. The top cross-piece, *b*, of the lower inner sash, *B*, and the bottom cross-piece, *c*, of the upper inner sash, *A*, have their adjacent edges rabbeted, so as to fit 5 snugly against each other. The top cross-piece, *d*, of the upper inner sash, *A*, is grooved to receive the tongue formed on the top inner cross-piece, *e*, of the frame.

The bottom cross-piece of the outer lower 10 sash is grooved to receive a tongue formed on the cross-piece *R*² on the sill and the top cross-piece, *f*, of the outer lower sash, *D*, and the bottom cross-piece, *g*, of the outer upper sash, *C*, have their adjacent surfaces rabbeted to fit 15 snugly against each other. The top cross-piece, *h*, of the outer upper sash is provided with a groove in its top edge for receiving a tongue formed on the outer upper cross piece, *k*, of the frame.

20 The window-frame is provided with a cross-piece, *m*, against which the outer edge of the bottom cross piece, *g*, of the upper outer sash, *C*, can rest when said sash is raised. Adjacent to the inner surfaces of the bottom sashes, 25 *B* and *D*, latches *n* are pivoted in the window-frame in such a manner that they can be swung out to project over the inner surfaces of the side pieces of the lower sashes for the purpose of guiding the said sashes when they slide vertically.

30 The guides or stop beads *o* for the upper outer sash, *C*, extend downward only a short distance below the bottom edge of the said sash when the same is raised, as shown in Fig. 35 6, so as not to interfere with swinging the sash.

The operation is as follows: Ordinarily the windows are to be opened and closed by sliding them vertically. To slide the upper inner 40 sash, *A*, the handle *G*³ on the shaft *G* in the weight *F*⁴, at the right-hand side of the window-frame, is turned for the purpose of withdrawing the lower ends of the levers or prongs *F*⁵ from the lower notches, *F*⁷, in the groove *F*⁶, 45 whereby the weight is released, and at the same time the rod *H*⁶ is moved upward, and, acting on the angle lever *H*⁵, withdraws the bolt *H* from the notch *H*⁷ in the swinging edge of the upper inner sash, *A*, which is thus released. The weight *F*⁴ is then moved upward by pulling the handle *G*³ upward, the shaft *G* on which the handle is formed moving upward within the slot *G*², and as it moves upward it carries upward the sliding piece *G*⁵ in the dove-tailed groove, which sliding piece serves to cover the slot *G*⁶ when the weight is lowered. To raise the inner lower sash, *B*, the handle on the shaft *M*⁴, Fig. 12, is turned for the purpose of withdrawing the ends of the bolts 55 *M*⁵, so as to release said sash. The sash can then be moved up and down, the blocks *K*³ sliding with the sash as they are held in the notches *B*³ in the side edges of the sash. As long as the sash slides said blocks *K*³ are not held by the hook-levers *L*⁷. When the sash 60 is lowered as far as possible it is locked in place by the ends of the bolts *M*⁵, which pass

into apertures *M*⁶ in the plates *L*⁴. To raise the outer lower sash, the handle in the middle of the bottom cross-piece is turned for the purpose of withdrawing the bolts *M*⁵ from notches in plates in the sides of the window-frame, whereby said sash is released, so that it can be raised. Both lower sashes are balanced by the weights secured to the cords 75 passed over the pulleys in the manner set forth. The blocks *Q*³, to which the sash cords or chains *Q*⁴ of the lower outer sash are secured, are also held in notches in the side edges of the said outer lower sash, so as to slide up and down 80 with the same. To lower the outer upper sash, the shaft *G* at the left-hand side of the casing is turned for the purpose of disengaging the weight *S*⁴. At the same time the shaft *T*⁴ is moved upward, and, acting on the angle-lever *T*⁵, by means of the intermediate lever, *T*⁶, withdraws the bolt *T*⁷ from the notch in the side of the said upper outer sash. As the weight is raised the sash descends. When the upper, inner, and outer sashes are lowered as far as 90 possible, their weights are locked in place at the proper elevation by the lower ends of the prongs or levers *F*⁸, which snap into the notches *F*⁹ in the sides of the grooves *F*⁶ and *S*⁶. When the inner upper sash, *A*, is moved down the 95 upper hinge-pin, *I*⁷, passes into the sliding socket *I*⁶, mounted to slide on the rod *I*⁴, and said socket and pin descend until the socket arrives at the bottom of the said rod, where it is held. The lower pin, *J*⁷, passes into the 100 fixed socket *J*⁶. The sash can then be swung toward the interior of the room, as the cord or chain *F* is connected with the sash at the pivoted edge only, as shown in Fig. 9, and thus does not interfere with swinging the window 105 out. The sash can be swung out only when lowered, and then only when the hinge-pins are in their proper positions in the hinge-sockets. The inner lower sash, *B*, cannot be swung in the direction toward the interior of 110 the room as long as the upper inner sash is raised, as the top rail, *b*, of the lower inner sash rests against the lower rail, *c*, of the upper inner sash when the lower inner sash is lowered and the upper inner sash is raised. 115 When the inner lower sash is lowered as far as possible the upper hinge-pin, *O*⁷, is in the upper socket, *O*⁶, and the lower hinge pin, *P*⁷, is in the lower socket, *P*⁶, the half-socket *P*⁸ being pressed back into the cavity provided for the 120 same. Before the said sash can be swung out it is necessary for the blocks *K*³, to which the cords or chains *K*⁴ are secured, to be disengaged from the sash and held. To accomplish this the sash is raised and the hinge-pins *O*⁷ and *P*⁷ partly withdrawn from their sockets until the lower hinge-plate in which the lower hinge-pin, *P*⁷, is secured has been raised sufficiently to permit the spring to press out the half-socket *P*⁸, the pin *P*⁷ resting against the same. 125 Then the shaft *M*⁴, on which the cross-piece *M*³ is secured, and which shaft is in the bottom cross-piece of the inner lower sash, *B*, is turned for the purpose of moving the slid- 130

ing bolts M' from each other, causing their ends to enter the apertures L^5 in the plates L^4 , and to act on the lower ends of the hook-levers L' , pressing said lower ends in the direction 5 from the edges of the sash and thereby forcing the upper ends of said hook-levers through the slots K^4 of the blocks K^3 , thus locking the blocks in place. The hooks of the said levers L' are held in the slots K^4 of the blocks K^3 against the action 10 of the springs by the weights on the other ends of the cords attached to the said blocks. The bolts M' are then withdrawn, and the sash can be swung in the direction toward the room. When the sash is swung back into its place 15 in the frame, the handle is first turned for the purpose of moving the sliding bolt N' , which acts on the cam-piece P^5 , connected with and adjacent to the half-socket P^4 , for the purpose of pressing the said half-socket through the 20 slot, so as to permit of lowering the sash until the hinge-pins O' and P' are fully in their sockets O^2 and P^2 . By lowering the sashes the blocks K^3 , which have been passed into their notches B^3 in the side edges of the sash B , by 25 swinging the sash back into the frame, are moved downward, and thus are disengaged from the hooks L^2 on the upper ends of the levers L' , and the upper or hook ends of the levers are forced back into the recesses. The 30 sash is then locked in place by the ends of the sliding bolts M' , which pass into the apertures M^3 .

It is evident that before the lower sashes can be swung out into the room the latches n (shown in Fig. 1) must be swung back. The lower outer sash cannot be swung in the direction toward the room until the lower inner sash has been swung in said direction.

To swing the lower outer sash in the direction toward the room, the handle in the middle of the same is turned for the purpose of withdrawing the ends of the bolts M' in the bottom cross-piece of the said lower outer sash from the notches in the casing. Then the sash 40 is raised slightly and the ends of the bolts R^3 are passed through the slots Q^6 in the extensions Q^5 of the blocks Q^3 , to which the sash cords or chains Q' of the said outer lower sash are secured, and thereby the said blocks Q^3 45 are locked in place. The sash can then be swung in the direction toward the room.

Before the upper outer sash, C , can be swung in the direction toward the room it must be lowered, which is accomplished in the manner 50 described. As the sash C descends, the cam-piece W on the lower hinge-plate, V , strikes the rounded edge of the cam-piece U^4 , connected with the sliding socket U^2 , and presses said socket into the recess provided 55 for it, so as to permit the sash to pass down. After the cam-piece W on the lower hinge of the upper outer sash has passed the sliding socket-piece U^2 , the spring, acting on the said 60 socket-piece, forces the same out, and the upper hinge-pin, U' , on the upper outer sash passes into said movable socket U^2 , and the

lower hinge-pin, V' , on the upper outer sash passes into the lower socket V^2 . The said upper outer sash can then be swung in the direction toward the room, as the sash-cord does not interfere, the same being secured to or connected with the sash at the pivoted edge of the same. When the sashes have been 70 swung into the room the panes and frames can be cleaned, repaired, &c.

To bring the sashes back into their normal positions—that is, to adjust them to slide—the upper outer sash is first swung back into its frame, and is then raised by moving its weight downward. Then the lower sash is swung into 80 place in the frame, and the movable half-socket of the hinge is pressed back by means of the sliding bolt N' , which is also provided in the bottom cross-piece of said outer sash. Then the sash is moved down until its hinge-pins are 85 fully in their sockets, the bolts R^3 are withdrawn from the slots Q^6 in the projections Q^5 on the blocks Q^3 , in which the sash-cords Q' of the said outer sash are secured, and the said sash is ready to be moved up and down. Then 90 the inner sash is swung back and adjusted in the manner previously described, and then the inner upper sash is swung back and raised.

It is evident that our improvements can also be applied on windows having two sashes 95 only—that is, upper and lower sashes.

Having thus described my invention, I claim as new and desire to secure by Letters Patent—

1. The combination, with a vertically-sliding sash, of hinges on which the sash can 100 swing and of detachable sash-cord fasteners by which the cords are held on the sash, substantially as herein shown and described.

2. The combination, with a vertically-sliding sash, of hinges on which the sash can 105 swing, a sash-cord fastener detachably held on the sash, and means for disengaging the fastener and holding the same when the sash is swung on its hinges, substantially as described.

3. The combination, with a sash, of a sash-cord secured to the same, a weight secured to the sash-cord, and a handle-piece for raising or lowering the weight, substantially as herein 110 shown and described.

4. A sash-weight provided with catches for 115 locking it in place, substantially as herein shown and described.

5. A sash-weight provided with a handle for lifting it, substantially as herein shown and described.

6. A sash-weight provided with a handle and locking devices operated by the handle, substantially as herein shown and described.

7. A sash-weight provided with a handle, crossed locking-levers pivoted on the weight 125 and acted upon by a spring, and a cam-piece on the handle, which cam-piece acts on the levers, substantially as herein shown and described.

8. The combination, with a sash, of a cord 130 secured to the same, a weight on the sash-cord, a handle-piece on the weight, which handle-

piece is provided with cams, a rod acted upon by one of the said cams, and a latch for locking the sash in place, on which latch the said rod acts, substantially as herein shown and 5 described.

9. The combination, with a window-frame, of a vertically-sliding sash, two hinge-plates on said sash, which hinge-plates are provided with hinge-pins, a fixed socket secured on the 10 window-frame and serving to receive the lower hinge-pin, and a socket mounted to slide on a rod on the window-frame and serving to receive the upper hinge-pin, which sliding socket is above the lower hinge-plate of the sash, substantially as herein shown and described.

10. The combination, with a sliding sash, of blocks resting loosely in notches in the side edges of the same, sash-cords secured to said blocks and passing over pulleys, and weights 20 on said sash-cords, substantially as herein shown and described.

11. The combination, with a vertically-sliding sash, of blocks in notches in the side edges of said sash, which blocks have slots, cords secured to the blocks and passed over pulleys, weights on said cords, and pivoted hooks in the window-frame for the purpose of holding the said blocks to which the sash-cords are fastened, substantially as herein shown and 30 described.

12. The combination, with a vertically-sliding sash, of blocks held in notches in the side edges of the same, sash-cords secured to the blocks, weights secured to the sash-cords, hook-levers pivoted in recesses in the window-frame, and sliding bolts held in the bottom cross-piece of the sash and connected with the cross-piece of a handle, substantially as herein shown and described.

13. The combination, with a vertically-sliding sash, of blocks in notches in the side edges of the sash, cords secured to said blocks, weights on the ends of the cords, hook-levers pivoted in the window-frame and serving to hold said 40 blocks in a lowered position, hinge-plates provided with pins on the sash, sockets on the window-frame, and a movable half-socket above the lower socket on the window-frame, substantially as herein shown and described.

14. The combination, with a vertically-sliding sash, of blocks held in notches in the side edges of the same, cords secured to said blocks, sash-weights secured to the cords, hook-levers pivoted in the window-frame for holding the 50 blocks in the lowered position, sliding bolts in the bottom cross-piece of the sash, hinge-plates on the sash, pins on the hinge-plates, sockets secured on the window-frame for receiving the hinge-pins, a half-socket above the bottom socket on the window-frame, which half-socket is mounted to slide through the side of the frame, and of a bolt connected with one of the bolts in the bottom of the sash and serving to press back the half-socket, substantially as 60 herein shown and described.

15. The combination, with a sliding sash, of

blocks held in notches in the side edges of the same, sash-cords secured to the blocks, weights secured on the sash-cords, hook-levers in notches in the window-frame for holding the 70 said blocks when lowered, bolts in the bottom cross-piece of the sash, hinge-plates on the sashes, hinge-pins projecting downward from the hinge-plates, sockets on the window-frame, a movable half-socket above the lower socket 75 on the window-frame, which half-socket can be passed through the side of the frame, a cam-piece connected with the half-socket, and a bolt connected with the bolts in the bottom cross-piece of the sash and serving to act on 80 the cam connected with the sliding half-socket, substantially as herein shown and described.

16. The combination, with a sash, of blocks held loosely in notches in the side edges of the same, with which blocks the sash-cords are 85 connected, hook-levers pivoted in the window-frame, and sliding bolts in the bottom cross-piece of the sash, which sliding bolts can act on the lower ends of said hook-levers and engage the upper ends with the blocks on the 90 sash, substantially as herein shown and described.

17. The combination, with a sash having notches in the side edges, of blocks in said notches, which blocks are provided with slots, 95 sash-cords secured on the blocks, weights secured to the sash-cords, the plates L⁴, secured in the sides of the window-frame, and provided with slots L³, L⁵, and M³, the hook-levers L¹, pivoted in recesses behind said plates, and 100 the sliding bolts M¹ in the bottom cross-piece of the sash, which bolts serve to act on the hook-levers L¹, and also to pass into the apertures M³, and thus lock the sash in place when lowered, substantially as herein shown and 105 described.

18. In a window, the combination, with a lower inner and upper inner and an outer lower and outer upper sash, of weights mounted to slide in the sides of the window-casing, one 110 of said weights being connected with the upper inner sash and the other weight with the upper outer sash, and of sash-cords secured to weights in the casing, which sash-cords have their other ends fastened to blocks held detachably on the sides of the outer and inner lower sashes, and of hinges for swinging the several sashes, substantially as herein shown and described.

19. The combination, with an inner upper 115 and lower sash and an outer upper and lower sash, of hinge-plates on the several sashes, which plates are provided with hinge-pins, fixed hinge-sockets on the lower sashes, and of fixed and movable hinge-sockets on the upper 120 sashes, substantially as herein shown and described.

20. The combination, with a window-frame having a vertical slot in each upright side piece, of a weight sliding in the box behind 125 the slot, a handle projecting from the weight through the slot, and a slotted sliding plate in

a groove on the slotted side of the box, which sliding plate serves to cover the slot in the box, substantially as herein shown and described.

21. The combination, with a window-frame, 5 of upper and lower outer and upper and lower inner sashes mounted to slide and to swing on hinges, handles secured to the weights of both upper sashes, locking devices for locking both 10 upper sashes, which locking devices are operated by the handles on the weights, sliding

bolts in the bottom cross-pieces of the lower sashes, and handles for operating said bolts in the bottom cross-piece of the lower sashes, substantially as herein shown and described.

Prague, June 10, 1885.
